CLOTHES PEG

Filed April 1, 1926

UNITED STATES PATENT OFFICE.

HENRY JAMES DREW, OF BRUNSWICK, JOHN ALFRED HUGHES DREW, OF ELSTERNWICK, AND JOHN FRANCIS GARDINER, OF GARDENVALE, VICTORIA, AUSTRALIA, ASSIGNORS TO WING CLOTHES PEG PROPRIETARY, LIMITED, OF ELSTERNWICK, AUSTRALIA.

CLOTHES PEG.

Application filed April 1, 1926, Serial No. 98,956, and in Australia April 7, 1925.

This invention relates to improvements in clothes pegs and refers especially to clothes pegs for securing garments and the like to a clothes line from which they are suspended 5 to dry.

One of the disadvantages with the ordinary wooden clothes pegs at present in use is that when they are forced over the clothes on the line there is a tendency for them to 10 spring off especially if there is a strong wind blowing.

The object of the present invention is to provide a clothes peg which is durable in construction, economical in manufacture and 15 will exert a tight grip on the clothes suspended from a line irrespective of the thickness of the line or whether the articles suspended therefrom are of a coarse or fine texture.

20 We accomplish the above mentioned object by forming a peg of a pair of separately formed gripping jaws which are pressed together by looped pieces of resilient wire. The jaws are formed at their gripping ends 25 with transversely disposed recesses which accommodate the central part of the looped wire and the ends of the said wire bear against the outside of the jaws near the top thereof and maintain the said jaws pressed 30 firmly together.

In order that the invention, the object and 35 nature of which have been set forth, may be readily understood reference will now be had to the accompanying sheet of explanatory drawings, wherein—

Figure 1 is a view in perspective illustrating a piece of shaped wood from which a number of gripping jaws may be cut.

Figure 2 is a view in perspective of two 40 pieces of shaped wood held together by looped pieces of wire and as assembled prior to cutting the pieces of wood transversely to form a number of complete pegs in accordance with the invention.

Figure 3 is a view in elevation of a looped 45 piece of wire employed to maintain the gripping jaws of a peg pressed together.

Figures 4 and 5 are views in front and side elevation of a peg.

50 Figure 6 is a view in perspective of a modified form of peg.

In these drawings like characters of reference have been employed to indicate the same

parts in the different views and the letter *a* designates a piece of resilient wire preferably galvanized or provided with some anti-corrosive coating, which is bent into a loop of circular or other approved shape, with the two ends bent inwardly to lie more or less parallel or at an angle to each other, see Figure 3.

The gripping jaws *b* may be formed from rectangular pieces of wood or other material and their lower ends are splayed to form a V-shaped opening *c* which will permit the peg being easily attached to a clothes line. The inner ends of the splayed ends of the jaws can terminate in circular recesses *d* which are shaped to enable a more effectual grip to be obtained on the clothes line.

A deep longitudinal recess *e*, preferably a saw-cut, is made in the lower end of each jaw at right angles to the V-shaped opening *c* and these recesses are in the same plane and are adapted to accommodate the central part 75 of the resilient wire *a*. The ends or inwardly turned parts of the loops of resilient wire can be bent slightly (as indicated by dotted lines at *f* in Figure 4) to ensure them obtaining a "bite" on the sides of the peg or alternatively a small hole or recess may be made in each jaw to accommodate the bent ends of the wire and so retain the wire correctly in position.

The loop-shaped piece of resilient wire can 85 be made circular or curved and the ends fitted into holes formed in the outer sides of the jaws, as shown in Figure 4, or they can be given any other approved shape that will give the greatest efficiency in use.

90 One simple and economical method of constructing pegs in accordance with the present invention is to shape a number of flat pieces of wood as shown in Figure 1. Two of these pieces of shaped wood are then 95 placed face to face as shown in Figure 2 and looped pieces of wire *a* are inserted into the longitudinal recesses *e* and pushed inwardly until the returned ends of the wires bear against the upper parts of the gripping 100 jaws, as shown.

When looped pieces of wire *a* have been placed in all the recesses the pieces of wood are cut or sawn transversely midway between the said recesses as indicated by the dotted 105 lines at *g* in Figure 2, thereby forming a

peg at each cut. The sides of the completed peg can be smoothed by means of a sand disc or in any other approved way.

In the modification of the invention shown in Figure 6 the looped pieces of resilient wire can be made circular and its ends accommodated in shallow longitudinal recesses *h* in the upper ends of the jaws *b* and the points of the said wire can be arranged to bear against the outer sides of the jaws at a point intermediate the ends thereof.

When the peg is forced on to the clothes line the wire will exert an increased pressure on the jaws and tend to force them together to ensure a firm grip on the article to which it is affixed. In Figure 4 of the drawings the two jaws are in their normal positions in full lines and in dotted lines in the position they occupy when the peg is placed on a clothes line.

A peg constructed as hereinbefore described is exceedingly simple in construction, will occupy a small space and in use will be found thoroughly efficient for the purpose for which it has been devised.

We claim:

1. A clothes peg comprising a pair of separately formed jaws having longitudinally disposed recesses in the corresponding gripping ends thereof, and a loop of resilient wire having its central part extending through and engaged by the recesses and its ends bearing against and pressing the jaws together.

2. A clothes peg comprising a pair of separately formed jaws having splayed gripping ends deep longitudinally disposed re-

cesses in the gripping ends of the jaws at right angles to the splayed gripping ends, and a loop of resilient wire having its central part engaged by the longitudinal recesses and its ends bearing against outsides of the said jaws.

3. A clothes peg comprising a pair of jaws formed of material of rectangular shape in cross section, splayed gripping ends on the jaws adapted to form a V-shaped entrance therebetween, longitudinally disposed recesses in the gripping ends of the jaws at right angles to the V-shaped entrance, a looped piece of resilient wire having its central portion engaged by the recesses, and inwardly turned ends on the looped piece of wire adapted to bear against the jaws to keep them pressed resiliently together.

4. A clothes peg comprising a pair of gripping jaws, a splayed opening between the gripping ends of the jaws, circular recesses in the gripping faces of the jaws at the upper end of the splayed entrance thereto, longitudinal recesses in the gripping ends of the jaws at right angles to the splayed entrance, and a looped piece of resilient wire having its central part extending through and engaged by the longitudinal recesses above the said circular recesses and its ends bearing against the outsides of the jaws.

In witness whereof we hereunto affix our signatures.

HENRY JAMES DREW.

JOHN ALFRED HUGHES DREW.

JOHN FRANCIS GARDINER.
